No. 36,308.

Patented May 5, 1903.

UNITED STATES PATENT OFFICE.

CARL E. BROWN, OF COLUMBUS, OHIO.

DESIGN FOR A STRINGED-MUSICAL-INSTRUMENT BODY.

SPECIFICATION forming part of Design No. 36,308, dated May 5, 1903.

Application filed March 25, 1903. Serial No. 149,591. Term of patent 14 years.

To all whom it may concern:

Be it known that I, CARL E. BROWN, a citizen of the United States, residing at Columbus, in the county of Franklin and State of Ohio, have invented a certain new, original, and ornamental Design for a Stringed-Musical-Instrument Body, of which the following is a specification.

This invention relates to a new and original design for stringed-musical-instrument bodies, and has for its object to provide a design of this character which shall be both useful and ornamental.

The characteristic features of the present design reside in a flat body having its lower end convex, from which its opposite sides converge upwardly in substantially straight lines, one of said sides merging into a reduced longitudinal neck portion terminating 20 at its outer end in a laterally-enlarged convex head, the adjacent edge of the neck having an intermediate substantially semicircular reentrant position or recess, the opposite edge of the neck having a bulged or convexed 25 portion located opposite the reentrant portion, from which said edge curves inwardly in opposite directions and terminates at its outer end in a concavity in the head, with its opposite end portion terminating in a 30 curved recess in the adjacent upper portion of the body, the thickness of the neck being less than the thickness of the body and the front of the latter having a central circular opening surrounded by a concentric groove.

35 In the drawings, Figure 1 is a front elevation of a musical-instrument body embodying the herein-described design. Fig. 2 is an edge elevation thereof.

Like characters of reference designate corresponding parts in both figures of the drawings.

The present design is characterized by a flat body 1, having a convex lower edge 2, from which its opposite side edges 3 and 4 converge upwardly in substantially straight lines, with 40 the edge 4 merging into a reduced longitudinal neck portion 5, that terminates at its outer end in a laterally-enlarged convex head 6. That edge of the neck into which the edge portion 4 merges has an intermediate 45 substantially semicircular reentrant portion or recess 7. The opposite edge of the neck has a bulged or convexed portion 8, located opposite the reentrant portion, from which said edge curves inwardly in opposite directions and terminates at its outer end in a concavity 9 in the head, with its opposite end portion terminating in a curved recess 10 in the adjacent upper portion of the body. As best shown in Fig. 2, it will be seen that the 50 neck portion is reduced in thickness. The front of body is provided with a central circular opening 11, and a concentric groove 12 extends around the edge of the opening.

Having thus described the invention, what 55 is claimed is—

The ornamental design for a stringed-musical-instrument body, substantially as shown and described.

CARL E. BROWN.
